US00D705153S

(12) **United States Design Patent**
Hall et al.

(10) **Patent No.:** US D705,153 S
(45) **Date of Patent:** ** May 20, 2014

(54) **WHEEL**

(71) Applicant: **Honda Motor Co., Ltd.**, Tokyo (JP)

(72) Inventors: **Jarad Hall**, Rancho Palos Verdes, CA (US); **Lev Wechsler**, Hermosa Beach, CA (US)

(73) Assignee: **Honda Motor Co., Ltd.**, Tokyo (JP)

(**) Term: **14 Years**

(21) Appl. No.: **29/469,100**

(22) Filed: **Oct. 7, 2013**

(51) LOC (10) Cl. **12-16**

(52) U.S. Cl.

USPC **D12/209**

(58) **Field of Classification Search**

USPC D12/204-213; 301/37.101, 64.101, 65, 301/64.201

See application file for complete search history.
